[57] CLAIM

The ornamental design for the ottoman, as shown and
described.

DESCRIPTION

FIG. 1 is a top view of the ottoman comprising my new
design;

FIG. 2 is a front elevational view thereof;

FIG. 3 is a left side elevational view thereof;

FIG. 4 is a right side elevational view; and,

FIG. 5 is a back elevational view thereof.

The broken lines are for environmental purposes only and
form no part of the claimed design.
